UNITED STATES PATENT OFFICE.

JEDDY D. NIXON, OF OKLAHOMA, OKLAHOMA.

APPARATUS FOR PUMPING OIL.

1,412,886.

Specification of Letters Patent. Patented Apr. 18, 1922.

Application filed March 12, 1921. Serial No. 451,802.

To all whom it may concern:

Be it known that I, JEDDY D. NIXON, a citizen of the United States, residing at the city of Oklahoma, in the county of Oklahoma and State of Oklahoma, have invented certain new and useful Improvements in Apparatus for Pumping Oil, of which the following is a specification.

This invention relates to oil wells and has for its object increase of the length of time 10 that the pumping apparatus within a well can be used without cleaning and also has another purpose, the reduction of the amount of sand friction and consequent wear of the 15 parts.

In the accompanying drawings forming part of this specification, in which like numbers of reference denote like parts wherever they occur, the figure is a vertical longitudinal 20 sectional view.

The well 1 within the earth 2 is in the usual form. Oil, sand, and mud, are present at 3 mixed together. The casing supporting the sides of the well is not shown in 25 the drawings.

The tubing anchor 4 is in the usual form, being a hollow cylinder and adapted to allow the oil etc. 3 to pass through it into the gas anchor 5. The standing-valve anchor 30 6 is hollow and is interiorly threaded at 7 and 8 for the attachment thereto, respectively, of the tubing anchor 4 and gas anchor 5.

Shoulder 9 serves as a seat for the barrel 35 or tube 10, which is interiorly threaded at 11 so as to screw upon the threads on the top of anchor 6.

Such heavy matter as sand and mud 12 as is deposited out of the flowing oil in the manner hereinafter described rests upon the top 40 surface or edge of standing valve anchor 6.

By the construction, arrangement, method of operation, and process of handling the oil with the sedimentary matter contained 45 therein, the quantity of sediment that may be accumulated within the barrel 10 is increased about one hundred fold over what is possible in such apparatuses at the present time, and, moreover, less sand and other 50 gritty matter reaches the working valve 13, and, therefore, friction and wear and tear on the said valve 13 and the working barrel 14, in which the same reciprocates, are greatly diminished. When an apparatus 55 such as this is filled to its capacity with sand,

mud, etc., it is necessary by means of machinery to pull out of the well the entire pumping apparatus, the length or extent of which is as great as the depth of the well, 60 which, as is well known, is often more than 2,000 feet. To reduce the frequency with which these parts are extracted from the well for cleaning means not only a saving in labor and expense, but also increases the output of the well because of less frequent interruption of the operation of the pump. 65

The suction by means of working-valve 13 draws the oil and its sedimentary contents through the passages within tubing anchor 70 4, gas anchor 5, and standing-valve anchor 6 and through the pipe 15 (threadedly connected at 16 in the head of anchor 6 and at its opposite end by thread 17 within cage 18) and the said pipe 15 conducts the oil 75 etc. to the baffle-bell 19 supported upon cage 18 and fastened thereto by nut 20. Thereupon the direction of flow of the oil and its sedimentary contents is changed or deflected by the said bell 19 and they are caused to flow downward past the lower edge 21 of bell 19, after which they flow upward outside and around bell 19 and within pipe 10 and through the passage 22 in coupling 23 and through valve 13 and working-barrel 80 14 and bushing 24 and pipe 25 and thence 85 outwardly to the surface of the ground.

The direction of flow of the oil and its sedimentary contents is indicated by the arrows in the drawing, the long arrows denoting oil and the short arrows the sand, 90 mud, etc.

The tortuous course of these materials downward within bell 19 and around the edge 21 thereof results in giving an opportunity to the sediment to settle to the point 95 12 and results in the oil being, to a very considerable extent, freed therefrom before reaching the working valve 13. Most of the oil that has passed valve 13 flows upward from barrel 14 through bushing 24, but part of it is deflected by the lower edge 26 of bushing 24, in the manner shown by the arrows, and, as the sedimentary matter is heavier than the oil, any that is therein will deposit from such point and be collected at 100 27 upon the upper edge 28 of coupling 23. Thus, the edge 26 acts as a baffle member. Moreover, the atmospheric pressure above valve 13 increases the tendency toward sedimentation. 105 110

The cross-sectional area of baffle bell 19 is approximately that of the pipe or barrel 10 within which the same is contained.

The pipe 15 is so anchored to valve anchor 6 and poised in barrel 10 free from magnetic contact with it that the magnetic circuit is completed only through anchor 6 exerting downward pull on the ball-valve 29. This prevents the said ball 29 from rising from its seat and lodging in the cage 18 above.

Having thus described this invention, I hereby reserve the benefit of all changes in form, arrangement, order, or use of parts, as it is evident that many minor changes may be made therein without departing from the spirit of this invention or the scope of the following claims.

I claim:

1. In a sand arresting mechanism for oil wells, an upper and lower tube having a hollow coupling therebetween, a barrel connected to the coupling and in spaced relation to the inner wall of the upper tube, a sucker operatively arranged in the barrel, an intake pipe arranged axially of the lower tube and adapted to communicate at its lower end with the space in which the oil is stored, a valve cage on the upper end of the intake pipe, a valve in said cage, said cage

having openings in its side for the passage of oil, and a baffle supported by the valve cage and guarding the openings for the passage of oil.

2. In an oil well equipment, a tubing, an intake pipe therein through which oil is circulated, a valve for controlling the intake pipe, a hood supported above the valve and extending downwardly in spaced relation to the inner wall of the tubing, and means below the depending hood for arresting foreign substances.

3. In a sand arresting mechanism for oil wells, an upper and lower tube having a hollow coupling therebetween, a working barrel connected to the coupling in spaced relation to the inner wall of the upper tube, a sucker operatively arranged in the working barrel, an intake tube arranged axially of the lower tube and adapted to communicate at its lower end with the space in which oil is stored, a valve seat on the upper end of the intake tube, a valve held in operative relation to the valve seat, and a baffle supported above the valve and deflecting the flow of oil passing the valve.

In testimony whereof I hereunto affix my signature.

JEDDY D. NIXON.
